UNITED STATES PATENT OFFICE.

GEORGE SEIBT, OF NEW YORK, N. Y., ASSIGNOR, BY MESNE ASSIGNMENTS, TO ATLANTIC COMMUNICATION COMPANY, A CORPORATION OF NEW YORK.

APPARATUS FOR PRODUCING POWERFUL ELECTRICAL OSCILLATIONS.

1,216,615.

Specification of Letters Patent.

Patented Feb. 20, 1917.

Application filed December 27, 1909. Serial No. 534,978.

To all whom it may concern:

Be it known that I, GEORGE SEIBT, a subject of the Emperor of Germany, residing at New York, in the county and State of 5 New York, have made a certain new and useful Invention in Apparatus for Producing Powerful Electrical Oscillations, of which the following is a specification.

This invention relates to apparatus for 10 producing electrical oscillations.

The invention has for its object the provision of means for the production of electrical oscillations and particularly slowly damped oscillations capable of being radiated, received and detected in the form of a 15 high musical note.

The invention consists substantially in the construction, arrangement, and combinations hereinafter more particularly explained, as 20 illustrated in the accompanying drawings, and finally pointed out in the appended claims.

In the drawings

Figure 1 is a view in diagram illustrating 25 certain arrangements including a primary oscillating circuit and a secondary oscillating circuit coupled thereto, for explaining the principles involved in my invention.

Figs. 2, 3, 4, 5, and 6, are oscillation or 30 wave diagrams.

Figs. 7, 8, 9, 10, 11, 12, 12_a, 13 and 14, are views showing various arrangements of electrodes and spark gaps adapted for use in attaining the objects and purposes of my 35 invention.

Figs. 15, 16, 17 and 18, are circuit diagrams showing various arrangements for carrying my invention into practical operation.

40 Fig. 19 shows an arrangement for charging the condensers in parallel and discharging them in series in connection with an operative embodiment of my invention.

Fig. 20 is a view showing the application 45 of a three phase alternating current generator employed to charge the condensers.

In Fig. 1 M is a source of current, in this case an alternating current generator, though in this respect my invention is not to be 50 limited or restricted. Where an alternating current source is employed, the generating circuit is coupled through a transformer, as indicated at D, with a circuit containing a spark gap S, the latter being shunted by a 55 circuit I, containing capacity, indicated at

C, and inductance, and this circuit I will hereinafter refer to as a primary oscillating circuit. This primary oscillating circuit is suitably coupled, inductively or otherwise, as through the inductance coils L, with a 60 second oscillating circuit as II.

In the arrangement shown in Fig. 1 two separate oscillations are produced, as is well known, even though the natural periods of the two circuits I and II, are the same. In 65 the case where these two circuits are in resonance with respect to their natural periods, the two wave lengths of the system are given by the following formulæ, neglecting resistance,—

$$\lambda_1 = \lambda_0 \sqrt{1 + K}$$

$$\lambda_2 = \lambda_0 \sqrt{1 - K}$$

in which λ_0 is the wave length of the circuits before coupling, and K is the coupling factor whose value is

$$\frac{M}{\sqrt{L_1 L_2}}$$

70

75

80

In Fig. 2 I have shown the form of the oscillations set up in the primary circuit I, and in Fig. 3 I have shown the form of oscillations induced or set up in the coupled secondary circuit II. An examination of 85 these diagrams reveals the fact that in the beginning when a spark discharge takes place in circuit I there is no energy in circuit II and consequently the oscillations in circuit I commence with maximum amplitude, while the amplitude of the oscillations in circuit II commence with zero value. The energy in the primary oscillating circuit I, however, sets up oscillations in circuit II, so that, commencing with zero value at the 90 beginning, the amplitudes of the oscillations in circuit II increase, as the corresponding amplitudes of the oscillations in circuit I decrease, thereby producing beats, the energy in circuit II influencing the circuit I 95 and again setting up oscillations therein, but of diminished value to the extent of the damping that takes place in the transformation from the one circuit to the other. These resulting oscillations of diminished 100 energy commence at zero value of amplitude and build up again in amplitude, in circuit I as the oscillations in circuit II diminish in amplitude, but the maximum value of the oscillations of the second beat in circuit I 110

is less than the maximum value of the oscillations in said circuit at the commencement of the operation, that is, at the time of the discharge at the spark gap. In turn these oscillations, of diminished maximum amplitude, in circuit I again set up oscillations in circuit II, but also of correspondingly reduced maximum amplitude, and so on, till the oscillations in both circuits are finally reduced to an infinitesimal value. For example, as shown in Figs. 2 and 3, at the instants of time indicated at U, T_2 , T_4 , etc., the energy is concentrated in circuit I and is at zero value in circuit II, the maximum value of the energy in circuit I at the point T_2 being less than at the point U and being less at point T_4 , than at point T_2 , and so on. At the instants of time indicated at T_1 , T_3 , T_5 , etc., the energy is concentrated in circuit II and is at zero value in circuit I, the maximum value of the energy in circuit II, being greater at point of time T_1 than at point of time T_3 , and greater at T_3 than at T_5 and so on. If, however, the natural periods of the two circuits I and II, are not in resonance with each other, oscillation beats may be produced which are imperfect and irregular in nature, and the energy which is transferred back and forth between the two coupled circuits, is only a lesser part of the entire discharged energy.

In the foregoing consideration it is assumed that the spark gap acts as an ordinary conductor and retains its conductivity until the energy of the discharge has been entirely dissipated. This condition is approximated as the metal of the spark gap electrodes becomes vaporized or as the quantity of current discharged through the spark gap is greater and the thermo conductivity of the materials employed for the spark gap electrodes is smaller. In practice these characteristics and conditions of the spark gap are never fully attained as is demonstrated by the familiar experiment showing that there always remains residual charge in a Leyden jar after discharging the same through a spark gap, which residual charge is capable of being discharged by reducing the length of the spark gap. Consequently, in practice, after a discharge of the condenser through the spark gap, such a condition of high resistance is created at the spark gap as to destroy its conductivity and its capacity to act as a conductor for the current before the discharge energy has been entirely dissipated, thereby, in effect, snapping off the further flow of current across the spark gap when the current intensity falls below a certain value. This property of the spark gap of snapping off the further flow of current thereacross when the current intensity falls to a certain value has the effect in coupled systems of opening the primary circuit at the

points of time indicated at T_1 , T_3 , T_5 , (Fig. 2), or at later similar periods of time, when the strength of the current in the primary circuit falls to zero, and the energy is just being concentrated in the secondary circuit, thereby, by opening the primary circuit, preventing the return or back flow of energy, at reduced intensity, from the secondary into the primary circuit. From the moment of this snapping off of the current at the spark gap, or the resulting opening of the primary circuit, the secondary circuit takes up an independent oscillation, uninfluenced to any appreciable degree by the coupling thereof to the primary circuit, the character of the oscillations therein being changed so that the two coupled waves λ_1 and λ_2 disappear and the free oscillation λ_0 alone, of the secondary circuit takes place, this free oscillation being of slowly damped form and depending on the natural period of the secondary circuit. In Fig. 4, I have shown the form of oscillation in the secondary circuit when the opening of the primary circuit, or snapping off action of the spark gap, occurs at the end of the first beat of the oscillations in the primary circuit, that is, at the instant of time indicated by T_1 , in Fig. 2, at which the current amplitude in the primary circuit has fallen to zero. From this point on the free oscillations in the secondary circuit continue in the form of slowly damped waves, as indicated in Fig. 4. In Fig. 5 I have shown the form of oscillation in the secondary circuit when the opening of the primary circuit, or snapping off action of the spark gap, occurs at the end of the second beat of the oscillations in the primary circuit, that is, at instant of time indicated at T_3 , in Fig. 2, and from this time on the oscillations in the secondary circuit are slowly damped free oscillations, commencing with an amplitude diminished as compared with the amplitude of the free oscillations in said circuit when the snapping off of the spark gap occurred at the end of the first beat of the oscillations in the primary circuit. Consequently the earlier the primary circuit is opened, after a spark discharge takes place, that is the earlier the spark is snapped off, as above explained, the stronger will be the initial free oscillations in the secondary circuit, as compared with the oscillations of the coupled systems. Should the spark gap snap off after the first beat in the primary circuit, that is at the instant of time indicated by reference letter T_1 , then the coupled wave practically disappears and the natural oscillation alone remains, provided the coupling of the systems is sufficiently strong. On the other hand, if the spark does not snap off until a later period of time in the succession of beats, then its coupled waves become more powerful and the free oscillations in

that case can be observed only with difficulty.

In Fig. 6, I have shown the resonance curve of the coupled system where the spark snaps off rapidly.

From the foregoing considerations it will be seen that in practical operation it is desirable that the spark snaps off, or is quenched, or, in another expression of the idea, that the primary circuit is opened, at the instant when the current amplitude first reaches zero value in the primary circuit, or at the spark gap, and that the duration of the spark be as short as possible, that is, that the coupling between the circuits shall be sufficiently strong or close and adjusted to secure a rapid decrease of the oscillations in the primary circuit with corresponding reduction of the energy in the primary circuit to substantially zero value as indicated by the diagrams, in which case the maximum of efficiency is attained in the transformation of energy from the primary to the secondary circuit.

In successfully accomplishing the rapid transfer of energy from the primary to the secondary circuit, in accordance with my invention, I propose to utilize, in practice, and in some forms of embodiment of apparatus, the general principles familiarly employed in the production of undamped electrical oscillations by the arc method, with certain modifications thereof, as will be pointed out hereinafter.

In the practical attainment of the objects, purposes and advantages of my invention, many specifically different constructions and arrangements of spark gap terminals may be employed, and having the property or characteristic of opening the primary circuit, or snapping off, as above explained.

In Fig. 7, I have shown such a spark gap in which are employed hollow electrodes 21, 22, containing water, as shown. With this arrangement it will be evident that the temperature of the electrodes will not exceed the boiling point of water.

In Fig. 8, I have shown an arrangement wherein the electrodes 23, extend into an air tight chamber 24. By thus excluding the oxygen of the air from the spark gap terminals, the surface of the electrodes is prevented from oxidizing, and since oxidation interferes with the conduction of the heat developed in the electrodes, I have found it very important to keep the surfaces of the electrodes free from oxid. I may also, if desired, maintain the spark gap in an atmosphere of a gas, or gaseous compound, or mixture possessing a high thermal conductivity, such for instance as hydrogen gas, the chamber, as 24, being filled with such gas, compound or mixture.

In Fig. 9 I have shown another arrangement of spark gap suitable for use in car-

rying my invention into practical use, wherein the spark gap terminals, or electrodes 25, are presented toward each other in the lower or cold portion of a flame 26. I have found an alcohol flame suitable for the purpose, but do not wish to be limited in this respect, as, instead of an alcohol flame, I may use any combustible mixture containing hydrogen.

In Fig. 10, I have shown a plurality of spark gaps with the electrodes 27 thereof connected up in series.

In Fig. 11, I have shown a plurality of spark gaps arranged within an airtight chamber 28, into which the terminals or electrodes 29, extend, the said electrodes or terminals being connected up in series.

In Figs. 12 and 12_a, I have shown an arrangement of spark gap possessing the necessary requisites for the attainment of the objects and purposes of my invention, wherein the desired dissipation of heat and artificial cooling is accomplished by increasing the surface area of the electrodes. In this case the electrodes or spark gap terminals, are in the form of disks, 31, separated from each other by an insulating washer 30, interposed therebetween, said disks having extended heat radiating or dissipating surfaces.

In Fig. 13, I have shown a plurality of such disks 32, superposed the one upon another, and each separated from the next adjacent one on either side thereof by insulating washers 33.

Fig. 14 shows a plurality of disks 34, superposed upon but separated from each other by insulating washers 35, the disks being held between two clamp heads 36, 37, with heavy insulation 38 interposed between the clamp heads and outer disks, said heads being held together by a central rod 39, passing centrally through the disks but insulated therefrom by the insulating sleeve 40.

I have found it preferable to employ electrodes having a high thermal conductivity, such as silver, copper, gold or bronze.

In the case of the disk form of electrode, as shown in Figs. 12 to 14, inclusive, each disk may be provided with a groove 41, see Figs. 12 and 12_a, on each face thereof, said grooves being concentric with the geometric center of the disk, and outside of the grooves 41, the disks may have a narrow flat portion 42, and it is between these flat peripheral portions that the insulating washers 30, 33, 35, are interposed, thereby leaving the central portions of the disks very slightly separated from each other, as indicated at 43, to form the spark gap. Beyond or outside of the bearing portions 42, the disks are provided with extended peripheral flanges 44, which, if desired, may be of decreasing thickness outwardly. By this construction of disk electrodes, it will be seen that I

provide electrodes which are exceedingly efficient in their heat conducting and radiating characteristics, thereby enabling me to secure the desired functioning of the electrodes, in accomplishing the snapping off, or quenching, of the spark discharge, or opening of the primary circuit, in accordance with the principles of my invention, and in a most efficient manner.

10 In all cases the spark gap between the electrodes should be very short.

While I have shown various specific forms of electrodes and arrangements thereof as operative embodiments of the principles of my invention, I do not desire to be limited or restricted, in the broad scope of my invention, as defined in the claims, to any specific form, construction, or arrangement of the electrodes, and many other specific structures of electrodes might be employed without departure from my invention.

In carrying into practical operation various circuit arrangements may be employed. Thus, in Fig. 15, I have shown a plurality of spark gaps F, fed from a suitable source of current, which may be either a direct current source or an alternating current source. In the particular form shown an alternating current generator M, is employed. The spark gap F is shunted by a circuit containing capacity, such as a condenser C, and an inductance, such as a self induction coil S₁, in series with each other, after the usual scheme of radio telegraphic arrangement. In practice, I prefer to employ an adjustable or variable self inductance S₁. The antenna A, may be associated with and coupled to the oscillating system which includes the spark gap, in any suitable or well known manner. In Fig. 15, I have shown the antenna system conductively coupled with the inductance S₁, and, if desired, an adjustable or variable self induction S₂, may also be included in the antenna system. Also, if desired, a current measuring instrument, such as a hot wire or other convenient form of ammeter indicated at J may be included in the antenna circuit. In practice, I propose to employ a current source having a potential such as is readily capable of breaking down, or effecting a disruptive discharge across the air space or spaces of the spark gap, and I have found a voltage of from 1000 to 100,000 suitable for my purposes.

In Fig. 16, I have shown a wire diagram in which the antenna A, is inductively associated or coupled with the primary oscillating circuit, as by inductively associating the coils S₁ S₂. In this case I also show an alternating current source M, the generating circuit carrying the current from the source M, being coupled to the primary oscillating circuit through a transformer P. 65 In this case I have also shown the con-

denser C and multiple spark gap F, transposed as compared with the arrangement shown in Fig. 15.

In Fig. 17, I have shown a usual form of circuit connections for radio telephony, employing a source of direct current, indicated at M', and containing resistance or choke coils L₃, L₄ in the leads thereof. A multiple spark gap F, has its terminals connected in the circuit of the source of current, and this 75 spark gap is shunted by an oscillating circuit containing a condenser C, and inductance S₁. The antenna A, is inductively associated with the primary oscillating circuit, through coils S₁ S₂, and a microphone 80 T, is connected in series in the grounded side of the antenna circuit.

In Fig. 18, I have shown a modification of the arrangement of Fig. 17, wherein an intermediate circuit R, having a low damping coefficient is interposed between the primary oscillating circuit and the antenna, otherwise the arrangement remains the same as above described with reference to Fig. 17, the intermediate circuit R being inductively 90 associated with the primary oscillating circuit through coils S₁ S₂, and the antenna being inductively associated with the intermediate circuit R, through coils S₄ S₂. The intermediate circuit R contains a condenser C₂ in the usual manner.

In Fig. 19, I have shown an arrangement whereby a plurality of condensers C₃, are charged in parallel and discharged in series through spark gaps F, each of the spark 100 gaps employing a plurality of terminals or electrodes or other arrangements for securing the snapping off action, as above explained. Self induction coils S₅ are interposed in series with the spark gaps and condensers. This arrangement is particularly advantageous because I am enabled to use several condensers which together give a large capacity without enlarging the wave length, that is to say: I discharge a large 110 quantity of energy without being obliged to change the wave length. Of course it is to be understood that the antenna is coupled to each of these induction coils S₅.

In Fig. 20 I have shown an arrangement 115 of three phased alternating current generator and the spark gaps and condensers coupled up in three corresponding and co-operating groups. With this arrangement when one spark gap has just finished discharging, and while the potential of the machine is momentarily below the discharge voltage, one of the other spark gaps will perform its function.

In the art of wireless or radio telephony 125 it is of great importance that the individual condenser discharges follow each other closely thereby increasing the audible frequency to such a point that it will no longer produce a material disturbance in the tele- 130

phone at the receiving station. I am convinced that it is not necessary to increase this group frequency so as to approach the limit of audition since it is possible to distinguish the human voice above such minor disturbances. In support of this conclusion it is only necessary to refer to the wire telephone systems in daily use in which, almost invariably, there is just such a minor disturbance in the telephone and still the human voice can be well distinguished. This is due to the fact that when one's attention is concentrated upon the voice of the speaker these minor disturbances remain unnoticed.

15 In order to carry out the foregoing, I propose to employ the following methods:—

A. By the diminution of noise by the use of alternating currents of several thousand cycles, say 5000 or more per second, 20 and also by the production of a large number of partial discharges from each cycle.

B. By employing a direct current of high potential, say of 1000 or more volts, and since direct current machines cannot be 25 operated to secure or deliver potentials higher than about 8000 volts, I propose to use the method in which a plurality of condensers are employed, said condensers being charged in parallel and discharged in 30 series, as indicated in Fig. 19.

C. To use three phase alternating current and connect the spark gaps in three groups accordingly, so that when one spark gap has just finished discharging and while the 35 potential of the machine is momentarily below the discharge voltage, one or the other spark gaps will properly function.

In all cases we have on hand a method 40 for producing the required number of discharges per second. This I propose to do by regulating the source of current. Should one, for example, employ a resonance transformer operated by alternating currents, it is possible to get along with less discharges

45 per second, as is customary in the old spark telegraphic methods. By the use of an alternating current generator of several hundred or thousand cycles, I am enabled to produce a pleasant, musical note in the receiving station and can finally bring the succeeding discharges of the condenser so close together that we pass beyond the limit of human audition.

In order to get the required number of 55 discharges per second it is evident that there must be means at hand by which the potential to which the condensers are charged can be regulated.

From the foregoing description it will 60 be seen that, in accordance with the method embodying the principles of my invention, by opening the primary oscillating circuit through the snapping off of the spark discharge at the instant the current amplitude 65 at the spark gap attains zero value in a

system employing coupled or inter-related circuits I am enabled to produce slowly damped radiations which give a high musical note in the receiver, capable of being readily and easily distinguished notwithstanding ordinary interference, and by opening the primary oscillating circuit or snapping off the spark discharge at the instant the current amplitude in said circuit, or at the spark gap, first attains zero value, 70 or at the end of the first beat of the oscillation I am enabled to excite, radiate and utilize slowly damped waves of maximum energy, and by increasing the rate of condenser discharge, or spark discharge, I am 75 enabled to produce slowly damped wave trains which approach and finally pass the limit of audition, and which, therefore, even if within the range of audibility, are capable of being utilized for accomplishing the 80 transmission of articulate speech.

Having thus set forth the object and nature of my invention, and various means and arrangements, what I claim as new and useful, and of my own invention, and desire to secure by Letters Patent is,—

1. In an apparatus for developing powerful electrical oscillations comprising coupled primary and secondary oscillating circuits, a coupling between said circuits sufficiently strong and adjusted to cause a rapid decrease of the oscillations in the primary circuit and to produce substantially zero value of current amplitude in the primary circuit at the end of the first beat of 100 the oscillations in the primary circuit and a short spark gap in the primary circuit formed to rapidly dissipate the heat generated therein, whereby the spark is quenched and the primary circuit opened at the end 105 of the first beat and useful, powerful, slowly damped free oscillations are produced in the secondary oscillating circuit and the two coupled oscillations practically disappear.

2. In an apparatus for developing powerful electrical oscillations comprising coupled primary and secondary oscillating circuits, means for opening the primary oscillating circuit so quickly that thereby useful, 110 powerful and slowly damped free oscillations in the secondary oscillating circuit are produced and the two coupled oscillations are of no practical effect, comprising a coupling between said circuits sufficiently 115 strong and adjusted to cause a rapid decrease of the oscillations in the primary circuit and to produce substantially zero value of current amplitude in the primary circuit and a short spark gap in the primary circuit formed to rapidly dissipate the heat developed therein.

3. In an apparatus for developing powerful electrical oscillations comprising coupled primary and secondary oscillating cir- 130

- cuits, means for opening the primary oscillating circuit so quickly that thereby useful, powerful and slowly damped free oscillations in the secondary oscillating circuit are produced and the two coupled oscillations are of no practical effect, comprising a coupling between said circuits sufficiently strong and adjusted to cause a rapid decrease of the oscillations in the primary circuit and to produce substantially zero value of current amplitude in the primary circuit and a short spark gap having electrodes of high thermal conductivity in the primary circuit formed to rapidly dissipate the heat developed therein.
4. In an apparatus for developing powerful electrical oscillations comprising coupled primary and secondary oscillating circuits, means for opening the primary oscillating circuit so quickly that thereby useful, powerful and slowly damped free oscillations in the secondary oscillating circuit are produced and the two coupled oscillations are of no practical effect, comprising a coupling between said circuits sufficiently strong and adjusted to cause a rapid decrease of the oscillations in the primary circuit and to produce substantially zero value of current amplitude in the primary circuit and a short spark gap having metal electrodes of extended surface and high thermal conductivity in the primary circuit formed to rapidly dissipate the heat developed therein.
5. In an apparatus for developing powerful electrical oscillations comprising coupled primary and secondary oscillating circuits, a coupling between said circuits sufficiently strong and adjusted to cause a rapid decrease of the oscillations in the primary circuit and to produce substantially zero value of current amplitude in the primary circuit at the end of the first beat of the oscillations in the primary circuit and a short air-tight spark gap in the primary circuit formed to rapidly dissipate the heat generated therein, whereby the spark is quenched and the primary circuit opened at the end of the first beat and useful, powerful, slowly damped free oscillations are produced in the secondary oscillating circuit and the two coupled oscillations practically disappear.
6. In an apparatus for developing powerful electrical oscillations comprising coupled primary and secondary oscillating circuits, a coupling between said circuits sufficiently strong and adjusted to cause a rapid decrease of the oscillations in the primary circuit and to produce substantially zero value of current amplitude in the primary circuit at the end of the first beat of the oscillations in the primary circuit and a plurality of short air-tight spark gaps formed to rapidly dissipate the heat generated therein connected in series in the primary circuit, whereby the spark is quenched and the primary circuit opened at the end of the first beat and useful, powerful, slowly damped free oscillations are produced in the secondary oscillating circuit and the two coupled oscillations practically disappear.

7. In an apparatus for developing powerful electrical oscillations comprising coupled primary and secondary oscillating circuits, a coupling between said circuits sufficiently strong and adjusted to cause a rapid decrease of the oscillations in the primary circuit and to produce substantially zero value of current amplitude in the primary circuit at the end of the first beat of the oscillations in the primary circuit and a plurality of short spark gaps connected in series in the primary circuit formed to rapidly dissipate the heat generated therein, whereby the spark is quenched and the primary circuit opened at the end of the first beat and useful, powerful, slowly damped free oscillations are produced in the secondary oscillating circuit and the two coupled oscillations practically disappear.

8. In an apparatus for developing powerful electrical oscillations comprising coupled primary and secondary oscillating circuits, means for supplying alternating current to the primary circuit, means for regulating the potential of the current supplied to the primary circuit to secure a regular spark frequency, a coupling between said circuits sufficiently strong and adjusted to cause a rapid decrease of the oscillations in the primary circuit and to produce substantially zero value of current amplitude in the primary circuit, and a short spark gap in the primary circuit formed to rapidly dissipate the heat generated in the gap whereby the spark is quenched and the primary circuit opened and useful, powerful, slowly damped free oscillations are produced in the secondary oscillating circuit and the two coupled oscillations practically disappear.

9. In an apparatus for developing powerful electrical oscillations comprising primary and secondary oscillating circuits, means for supplying energy to the primary oscillating circuit, a coupling between said circuits sufficiently strong and adjusted to cause a rapid decrease of the oscillations in the primary circuit and to produce substantially zero value of current amplitude in the primary circuit at the end of the first beat of the oscillations in the primary circuit and a short spark gap in the primary circuit formed to rapidly dissipate the heat developed in the gap whereby the spark is quenched and the primary circuit opened at the end of the first beat and useful, powerful, slowly damped free oscillations having a regular group frequency are produced in the secondary oscillating circuit and the two coupled oscillations practically disappear.

10. In an apparatus for developing powerful electrical oscillations comprising primary and secondary oscillating circuits, a coupling between said circuits sufficiently strong and adjusted to cause a rapid decrease of the oscillations in the primary circuit and to produce substantially zero value of current amplitude in the primary circuit at the end of the first beat of the oscillations in the primary circuit and a short spark gap in the primary circuit formed to rapidly dissipate the heat developed in the gap whereby the spark is quenched and the primary circuit opened at the end of the first beat and useful, powerful, slowly damped free oscillations are produced in the secondary oscillating circuit.

and the two coupled oscillations practically disappear, and means for regulating the potential of the source of energy supplied to the primary circuit in order to get the desired group frequency of oscillations to produce a clear note within the limit of audibility.

10. In an apparatus for developing powerful electrical oscillations comprising primary and secondary oscillating circuits, means for exciting electrical oscillations in the primary circuit having a regular group frequency, a coupling between said circuits sufficiently strong and adjusted to cause a rapid decrease of the oscillations in the primary circuit and to produce substantially zero value of current amplitude in the primary circuit at the end of the first beat of the oscillations in the primary circuit and 15 a short spark gap in the primary circuit formed to rapidly dissipate the heat generated therein, whereby the spark is quenched and the primary circuit opened at the end of the first beat and useful, powerful, slowly damped free oscillations are produced in the secondary oscillating circuit and the two coupled oscillations practically disappear.

11. In an apparatus for developing powerful electrical oscillations comprising coupled primary and secondary oscillating circuits, means for regulating the frequency of one of said oscillating circuits, and means for opening the primary oscillating circuit so quickly that thereby useful, powerful and slowly damped free oscillations in the secondary oscillating circuit are produced and the two coupled oscillations are of no practical effect, comprising a coupling between 30 said circuits sufficiently strong and adjusted to cause a rapid decrease of the oscillations in the primary circuit and to produce substantially zero value of current amplitude in the primary circuit and a short spark gap 35 in the primary circuit formed to rapidly dissipate the heat developed therein.

12. In an apparatus for developing powerful electrical oscillations comprising coupled primary and secondary oscillating circuits, means for preventing oscillations in the secondary circuit from reacting on the primary circuit after the first beat of the oscillations in the primary circuit, whereby powerful and slowly damped oscillations 50 of a single frequency are produced in the secondary circuit and the two coupled oscillations are of no practical effect.

13. In an apparatus for developing powerful electrical oscillations comprising closely coupled primary and secondary oscillating circuits, means for preventing transfer from the secondary circuit of energy received from the primary circuit, whereby powerful and slowly damped oscillations of 60 a single frequency are produced in the sec-

ondary circuit and the two coupled oscillations are of no practical effect.

14. In a transmitting apparatus for radio communication, an alternating current source of energy, a closed oscillation circuit fed from said source and containing a series divided spark gap constructed to rapidly dissipate the heat generated in the gap, and an antenna circuit, said circuits being closely coupled and adjusted to cause a rapid and substantially complete transfer to the antenna circuit of the energy produced in the closed circuit, whereby the spark is quenched to prevent the return of energy from the antenna circuit to the closed circuit and powerful slowly damped oscillations of single frequency are produced in the antenna circuit and the two coupled oscillations of the coupled circuits are of no practical effect.

15. In a transmitting apparatus for radio communication, an alternating current source of energy, a closed oscillation circuit fed from said source and containing a series divided spark gap constructed to rapidly dissipate the heat generated in the gap, an antenna circuit in resonance with said closed circuit and closely coupled thereto to cause a rapid and substantially complete transfer to the antenna circuit of the energy produced in the closed circuit, means for causing said groups of oscillations in said closed circuit to be uniformly spaced and to correspond in frequency to the alternations of current fed to the closed circuit, whereby the return of energy from the antenna circuit to said closed circuit is prevented and powerful slowly damped oscillations of single frequency are produced in and radiated from the antenna circuit having a regular group frequency and capable of producing in the telephone of the receiving apparatus a clear musical tone.

16. In an apparatus for developing powerful electrical oscillations, the combination with inter-related oscillating circuits comprising a primary oscillating circuit and a secondary oscillating circuit coupled together, of means for quickly opening the primary inter-related oscillating circuit, at the end of the first beat, permitting the current to pass in either direction and comprising a short spark-gap provided with electrodes of high thermal conductivity and a source of electrical current having a potential capable of quickly effecting a disruptive discharge across the spark-gap, and the coupling of said inter-related oscillating circuits being sufficiently strong and adjusted to secure such opening of the said oscillating circuit, whereby powerful, slowly damped free oscillations in the secondary oscillating circuit are produced and the coupled waves practically disappear, substantially as described.

17. In an apparatus for developing pow-

erful electrical oscillations, the combination with inter-related oscillating circuits comprising a primary oscillating circuit and a secondary oscillating circuit coupled together, having their natural periods in tune with each other, of means for quickly opening the primary oscillating circuit, at the instant of zero current therein, permitting the current to pass in either direction and 10 comprising a short spark-gap provided with electrodes of high thermal conductivity and a source of electrical current having a potential capable of quickly effecting a disruptive discharge across the spark-gap, and said 15 coupled inter-related oscillating circuits being provided with coupling varying means and the coupling of said circuits being sufficiently strong and adjusted to secure such opening of the said oscillating circuit, where- 20 by powerful, slowly damped free oscillations in the secondary oscillating circuit are produced and the coupled waves practically disappear, substantially as described.

18. In an apparatus for developing pow- 25 erful electrical oscillations, the combination with coupled oscillating circuits comprising a primary oscillating circuit and a secondary oscillating circuit and means for exciting oscillations in the primary circuit, of means 30 for quickly interrupting the coupled effect of said circuits to permit the secondary circuit freely to oscillate, permitting the current to pass in either direction and comprising a short spark-gap provided with electrodes of 35 high thermal conductivity and a source of electrical current having a potential capable of quickly effecting a disruptive discharge across the spark-gap, and said coupled oscil- 40 lating circuits being provided with coupling varying means and the coupling of said circuits being sufficiently strong to secure such quick interruption of the coupled effect of 45 said circuits, whereby powerful, slowly damped free oscillations in the secondary oscillating circuit are produced and the coupled waves practically disappear, substantially as described.

19. In an apparatus for developing pow- 50 erful electrical oscillations, the combination with a primary oscillating circuit and a sec- 55 ondary oscillating circuit, said circuits being coupled together, of means for exciting elec- trical oscillations having a group frequency below the upper limit of audibility in one of said circuits, and means for quickly opening 60 said excited circuit, permitting the current to pass in either direction and comprising a short spark-gap provided with elec- 65 trodes of high thermal conductivity and a source of electrical current having a potential capable of quickly effecting a disruptive discharge across the spark-gap, and the coupling of said inter-related oscillating circuits being sufficiently strong and adjusted 70 to secure such opening of the said oscillating

circuit, whereby powerful, slowly damped free oscillations in the secondary oscillating circuit are produced and the coupled waves practically disappear, substantially as described. 75

20. In an apparatus for developing pow- 75 erful electrical oscillations, the combination with coupled electrically oscillating circuits having natural periods in resonance with each other, of means for exciting electrical 80 oscillations in one of said circuits, and means for quickly opening the excited circuit after the first beat of the oscillations therein to permit the other circuit to oscillate in accordance with its free period, comprising a short spark-gap formed to rapidly dissipate heat generated therein and a source of electrical current having a potential capable of quickly effecting a disruptive discharge 85 across the spark-gap, and the coupling of said inter-related oscillating circuits being sufficiently strong and adjusted to secure such opening of the said oscillating circuit, whereby powerful, slowly damped free oscil- 90 lations in the secondary oscillating circuit are produced and the coupled waves practically disappear, substantially as described.

21. In an apparatus for producing slowly damped electrical oscillations, the combination with coupled electrically oscillating cir- 95 cuits, of a three-phased alternating current source for supplying energy to one of said circuits, said excited circuit having means for quickly snapping off the spark discharge in and opening said circuit consisting of 100 spark gaps corresponding in number and relative connection to the three phases of the alternating current source, the coupling of said inter-related oscillating circuits being sufficiently strong and adjusted to cause such 105 opening of the said oscillating circuit, sub- stantially as described.

22. In a system of wireless communica- 110 tion, a poly-phase alternating current source, an oscillating circuit fed from each phase 115 circuit of the source, each oscillating circuit constructed to produce oscillations of rapidly decreasing amplitude, and an antenna system common to all of the said oscillating circuits. 120

23. In a system of wireless communica- 125 tion, a poly-phase alternating current source, an oscillating circuit fed from each phase of the source, a quench spark-gap included in each oscillating circuit, and an antenna system common to all of said circuits. 130

24. In a system of wireless communica- 125 tion, a poly-phase alternating current source, an oscillating circuit associated with each phase circuit, an antenna system asso- 130 ciated with the oscillating circuits, and means for preventing oscillations in the antenna circuit from reacting on the oscillat- ing circuits.

25. In a system of wireless communica- 130

tion, a poly-phase alternating current source, an oscillating circuit associated with each phase circuit, and means for producing and radiating trains of powerful slowly 5 damped electromagnetic waves of single frequency from the oscillations in the oscillating circuits.

26. In a system of wireless communication a poly-phase alternating current source, an 10 oscillating circuit associated with each phase circuit, means for producing in said oscillating circuits oscillations of rapidly decreasing amplitude, and means for utilizing said oscillations of rapidly decreasing amplitude 15 for producing and radiating electromagnetic waves.

27. A wireless telephone transmitting system, including a source of alternating current supply having a frequency below the 20 upper audible limit, and a multiple spark gap, and means for modifying the radiated waves from such system by and in accordance with sound waves.

28. A wireless telephone transmitting system including a source of alternating current supply to a quenched spark gap, the alternating current having a frequency below the upper audible limit, in combination with means for modifying the generated oscillations by and in accordance with sound waves.

29. A wireless telephone transmitting system, having means for radiating slowly damped waves of audible group frequency, 35 and means for modifying the radiated waves by and in accordance with sound vibrations.

30. A wireless telephone transmitting system for radiating slowly damped waves 40 of audible group frequency and including a high frequency circuit, and a telephone transmitter device associated with said circuit to modify the oscillations therein by and in accordance with sound vibrations.

45 31. A wireless telephone transmitting system, comprising coupled primary and secondary oscillating circuits, means for supplying to the primary circuit an alternating current having a frequency below 50 the upper audible limit, a coupling between said circuits sufficiently strong and adjusted to cause a rapid decrease in the oscillations in the primary circuit and to produce substantially zero value of current amplitude 55 in the primary circuit, and a plurality of short air-tight spark gaps formed to rapidly dissipate the heat generated therein

connected in series in the primary circuit, whereby the spark is quenched and the primary circuit opened at the end of the first 60 beat and slowly damped free oscillations are produced in the secondary oscillating circuit and the two coupled oscillations practically disappear, and means for modifying the radiated waves by and in accordance 65 with sound vibrations.

32. In an apparatus for developing powerful electrical oscillations, a source of electrical energy, an oscillating circuit fed from said source and including a short 70 spark-gap formed to rapidly dissipate the heat generated therein, and means associated with said oscillating circuit adapted to produce beats through the spark gap causing a rapid decrease of the oscillations 75 through the gap with reduction of the amplitude of the oscillations of the current passing therethrough to substantially zero value at the end of a beat and said means providing a second oscillating circuit re- 80 ceiving energy from the first said circuit, whereby the first said circuit will be opened at the end of the first beat of the oscillations through the spark gap and powerful 85 slowly damped oscillations will result in the second said circuit.

33. In an apparatus for developing powerful electrical oscillations, a source of electrical energy, an oscillating circuit fed from said source and including a short 90 spark-gap formed to rapidly dissipate the heat generated therein, and means associated with said oscillating circuit adapted to produce beats through the spark gap causing a rapid decrease of the oscillations 95 through the gap with reduction of the amplitude of the oscillations of the current passing therethrough to substantially zero value at the end of a beat and said means providing a second oscillating circuit re- 100 ceiving energy from the first said circuit, whereby the first said circuit will be so quickly opened that powerful slowly damped oscillations will result in the second said circuit.

In testimony whereof I have hereunto set my hand in the presence of the subscribing witnesses, on this 17th day of December A. D., 1909.

GEORGE SEIBT.
